RADIO PROGRAM TIMING CLOCK

Walter A. Farrell, Miamisburg, Norman R. Williams, Dayton, and David M. Calihan, West Carrollton, Ohio

Application August 1, 1938, Serial No. 222,320

10 Claims.

(Cl. 200—37)

This invention relates to clock operated mechanism for timing electrical circuits, and is particularly adapted for automatically turning on a radio receiver, or similar device, at a pre-selected time and turning it off when the desired time has elapsed.

It is the constant experience of many radio listeners that, although they may fully intend to tune in a desired program which is yet several hours distant, unless they exercise considerable care, and spend considerable time watching the clock, part or all of the program is often over before the intention is again recalled.

It is therefore an object of this invention to provide a quickly and easily adjusted mechanism which will complete the electrical circuit to start a radio receiver at a predetermined manually selected time.

It has been a further experience of radio listeners that when a desired program comes to an end, they are often so situated that it is highly inconvenient to immediately turn off the receiver, with the result that they must often continue to hear matter in which they have not the slightest interest until they are in a position to more conveniently shut it off.

It is therefore another object of this invention to so construct the mechanism that it will instantly turn off a radio receiver set when a selected period of time, from the time at which it started, has elapsed.

Inasmuch as radio programs are substantially always limited to quarter hour periods, or to even multiples thereof, it is a further object of this invention to arrange the mechanism to facilitate manual selectivity by providing means operable to a single position to determine both the starting time and the duration period.

Another object is to provide clock operated electrical switch mechanism with adjusting means whereby the time of operation may be accurately controlled.

Further objects will become apparent to those skilled in the art to which the invention appertains as the invention is further described with proper reference to the accompanying drawings, wherein:

Fig. 1 is a front elevation of the device showing the face of the clock and the manually selective controls for determining the starting time and the duration of the electrical circuit.

Fig. 2 is a view looking from the top, part being a horizontal sectional view taken on the line 2—2 of Fig. 1, through the axes of the clock and clock operated switches and of the hour and minute

controls, the remainder being a plan view seen from the line 2a—2a.

Fig. 3 is a longitudinal vertical section viewed from the rear, the section being taken on the line 3—3 of Fig. 2 thereby showing the clock operated hour switch mechanism, the main switch, the manually selective hour control, and the manually selective quarter hour control.

Fig. 4 is a longitudinal vertical section viewed from the rear, the section being taken on the line 4—4 of Fig. 2, thereby showing the clock operated main quarter hour switch mechanism.

Fig. 5 is a longitudinal vertical section viewed from the rear, the section being taken on the line 5—5 of Fig. 2, thereby showing the clock operated auxiliary quarter hour switch mechanism.

Fig. 6 is a rear elevational view, looking from the line 6—6 of Fig. 2, showing the rotatable contact mechanism whereby electric current is conveyed from the rotatable auxiliary quarter hour switch to a non-rotatable member.

Fig. 7 is a section taken at 7—7 of Fig. 6 showing the same contact mechanism shown in Fig. 6 but from a different angle.

Fig. 8 is an elevational view of the rear panel, viewed from the line 8—8 of Fig. 2, showing two switch mechanisms, one manually and the other electrically operated, both cooperating with the clock operated electrical switches to effect making and breaking of the circuits.

Fig. 9 is a schematic representation of the device including a complete wiring diagram showing the various circuits to be made under different conditions of operation.

A given part is referred to by the same numeral in all views in which it appears.

Construction

To facilitate the mounting of a plurality of parts which must be electrically insulated one from the other, the cabinet 10 is preferably made of some form of insulating material, preferably molded plastic, wood, glass, or the like. It comprises a base 12 with feet 11, end walls 14, top cover 16, front panel 18, and rear panel 20. For purposes of inspection and assembly the rear panel may be hinged to the base preferably at 22 (see Fig. 8). A snap fastener 24 may be provided to hold the rear panel 20 closed. A small knob 25 may be provided to more conveniently pull the panel to open position.

Mounted on the inside of the front panel 18 and extending partway through an opening 26 therein is a twelve hour clock 28 having the usual hour hand 30 and minute hand 32. The clock

works may be of any known type mechanically or electrically operated, and since this matter is immaterial to the invention, the clock works are not shown. Whatever their nature, they may be enclosed in a clock case 34 having ears 36 through which screws 38 may extend to hold the clock secured to the inside of the front panel 18. A clock dial 39 and a crystal 41 are sprung into appropriately formed grooves in the interior of an annular rib 43 extending from the front panel forwardly.

Whatever the nature of the clock works it should have the usual central minute hand shaft 40 to which the minute hand is secured and which 15 rotates one revolution per hour and the usual twelve to one speed reducing gearing comprising a pinion 42 on the minute hand shaft, a large gear 44 on stud 46, a pinion 48 secured to the 20 large gear 44 to rotate therewith and a large gear 50 on the hour hand sleeve 52 by which the hour hand 30 is rotated.

Immediately rearward of the clock case 34 is the clock operated hour switch (see Fig. 3), the operating arm 54 which must rotate at the same 25 speed as the hour hand 30 of the clock, that is, one revolution in twelve hours. The means provided for rotating this switch operating arm at hour hand speed comprises a sleeve 56 runningly fitted to the minute hand shaft 40 and driven by 30 the minute hand shaft through a speed reducing gear train which is a duplicate of the one previously described for rotating the hour hand, that is, this gear train also comprises a pinion 42 fastened to the minute hand shaft 40, a large 35 gear 44 on a stud 46, a pinion 48 secured to the large gear 44, and a large gear 50 on the sleeve 56.

Twelve segmental contact members numbered consecutively from 57 to 68 are circumferentially equally spaced and insulatedly supported on the 40 hour switch base 70. The base 70 is preferably made of insulating material and the contact members 57 to 68 may be secured thereto, each by a single rivet 72 drawn reasonably tight, but not so tight but that the contact members may 45 be swung about the rivet, using it as a hinge pin.

Each contact segment 57 to 68 has a laterally extending ear 74, tapped for an adjusting screw 76. Bearing caps 78 held to the insulating base 70 by rivets 80 provide rotative bearing for the 50 adjusting screws and prevent axial movement thereof.

The hour switch contact blade 82 is hinged to the end of the operating arm 54 by the hinge pin 84. A contact roller 86 is rotatably supported 55 on a stud 88 at one end of the blade 82. The roller 86 has an annular groove around its periphery wide enough to fit the thickness of the contact segments 57 to 68 loosely. The end of the blade 82 opposite the roller is bent over to 60 provide an ear 90. One end of a coil spring 92 is hooked through a hole in the ear 90, the other end being hooked through a hole in the extension 94 of the operating arm 54. The spring 92 should have sufficient tension to keep the roller 86 65 pressed securely against the contact segments as the operating arm 54 rotates. Rotation is in the direction of the arrow 96.

The central opening 98 of the base 70 is of such diameter that the contact segments extend 70 over the edge of the opening considerably thereby preventing any interference of the roller 86 with the base.

If, during rotation, the roller 86 leaves the end 100 of any contact segment 57 to 68 several 75 minutes too soon, as may happen due to inac-

curacy of workmanship in the positioning of the segments the ends 100 may be adjusted inwardly with the screws 76, whereby the roller 86 may be made to leave that particular segment several minutes later. This is important because the roller 86 should leave each segment 57 to 68 at exactly the time that the minute hand points to twelve. The clock operated hour switch may be broadly designated by the numeral 101.

Rearward of the hour switch is the main quarter hour switch (see Fig. 4), the operating arm 102 of which must rotate at the same speed as the minute hand, that is, one revolution in one hour. To compel rotation of the arm 102 with the minute shaft 40, the arm is securely clamped 15 between two internally threaded collars 103 which are closely fitted to the external threads on the shaft.

Four contact segments 104, 105, 106, and 107 are circumferentially equally spaced and insulatedly supported on the main quarter hour switch base 108. The base 108 is preferably made of insulation, the contact segments each being hingedly held thereon by a rivet 110. Ears 112, extending laterally from the contact segments 104 to 107, are tapped to receive the adjusting screws 114, which are rotatably supported in the bearing caps 116, which are in turn secured to the base 108 by rivets 118. Adjustment of the contact segments of the main quarter hour switch is 20 accomplished in the same manner as described relative to the hour switch and for the same reason.

The main quarter hour switch contact blade 120 is hinged to the end of the operating arm 102 by the hinge pin 122. A contact roller 124 is rotatably supported on a stud 126 at one end of the blade 120. The roller 124 has an annular groove around its periphery which fits over the edge of the contact segments 104 to 107 freely. The end of the blade opposite the roller is bent over to provide an ear 128. One end of a coil spring 130 is hooked into a hole in ear 128, the other end being hooked into a hole in the extension 132 of the operating arm 102. The spring 130 should keep the roller 124 firmly in contact with the segments 104 to 107. Rotation is in the direction of the arrow 134. The clock operated main quarter hour switch may be broadly designated by the numeral 135.

Relative to the hour switch 101, Fig. 3, and the main quarter hour switch 135, Fig. 4, it should be noted that the minute shaft 40, the operating arms 54 and 102, the contact blades 82 and 120, and the contact rollers 86 and 124 are all made 55 of electrically conductive material and are all in electrical communication, one with the other, whereby an electrical circuit is always possible from any of the hour contact segments 57 to 68 upon which the roller 86 rests to any main quarter hour contact segment 104 to 107 upon which the roller 124 rests.

Immediately rearward of the main quarter hour switch shown in Fig. 4 is the auxiliary quarter hour switch (see Fig. 5), the operating arm 136 of which is made of insulating material. The arm 136 is secured to the minute shaft 40 for rotation therewith by clamping it between the two tapped collars 138 which fit the external threads on the shaft.

Four contact segments 139, 140, 141, and 142 are hingedly supported on the insulation base 143 by the rivets 144. Tapped ears 146 on the contact segments receive adjusting screws 148 which are rotatable in caps 150 fastened to the 75

base 143 by rivets 152. Adjustment of the auxiliary quarter hour contact segments is effected by the screws 148 in the same manner and for the same reasons as explained relative to the hour switch.

The auxiliary quarter hour switch contact blade 154 is hinged to the end of the operating arm 136 by the hinge pin 156. A contact roller 158 is rotatably supported on a stud 180 at one end of the blade 154. The roller 158 has an annular groove which receives the edges of the contact segments 139 to 142 freely. The end of the blade opposite the roller is bent to provide an ear 162. One end of a coil spring 164 is hooked into a hole in the ear 162, the other end being hooked in a hole in the end of a laterally projecting arm 166 of the U shaped spring conductor 168 (see Figs. 6 and 7).

The U shaped conductor 168 has one end secured to the insulation arm 136 by rivets 170. The other end extends axially at 172 and again radially at 174 to make contact with the surface of the contact blade 154. A metal pin 176 is pointed at the end, the pointed end extending into a corresponding opening in the U shaped conductor 168. The other end of pin 176 is shouldered and riveted into a T shaped conductor 178 (see Figs. 2, 6, and 7). A coil spring 180 has one end hooked into a hole in the end of conductor 178, the other end being hooked into a hole in an anchor strip 182. Rotation of the switch is in the direction of the arrow 181.

The clock operated auxiliary quarter hour switch may be broadly designated by the numeral 183.

Intermediate the main quarter hour switch base 108 and the auxiliary quarter hour switch base 143 is a bearing plate of insulation 184 with a small center hole runningly fitted around a collar on the minute shaft 40 whereby the shaft is steadied at its free end. Four long screws 186 extend through the switch bases 10, 108, and 143, the bearing plate 184, the conductor 178, and the anchor strip 182 into the front panel 18 of the cabinet 10 to support the several parts in proper alignment. Spacing sleeves 188, 190, 192, 194, and 196 hold the several parts properly spaced apart.

Since the operating arm 136 of the auxiliary quarter hour switch 183 is made of insulating material, obviously an electrical circuit may be completed by this switch only through the T shaped conductor 178, through pin 176, U shaped conductor 168, blade 154, roller 158 to whichever of the four contact segments 139 to 142 the roller is then touching.

Extending forwardly through the front panel 18 is the shaft 198 of the manually operable hour control switch. A hub 200 provides increased bearing length for the shaft. A hand knob 202 is secured to the outer end of the shaft by the pin 204 to facilitate manual rotation of the shaft.

Within the cabinet 10 on the inner end of the shaft 198 is the arm 206 which carries the contact plunger 208. A series of twelve contacts, numbered 210 to 221 inclusive, in the rear face of the front panel 18 are circumferentially equally spaced and concentric with the shaft 198 (see Fig. 3).

A compression spring 222 urges the plunger 208 always against any contact with which it may be aligned, (see Fig. 2).

The twelve contacts 210 to 221 are connected respectively, each by a separate wire, to the twelve hour-switch contact segments 57 to 68.

For clearness in illustration, the wires connecting these parts are not shown in Figs. 2 or 3, but are clearly shown in the complete wiring diagram Fig. 9. In order to make sure that the wires will not interfere with the rotation of the arm 206 and plunger 208, a series of grooves may be molded or otherwise provided in the inner face of the front panel 18. Such grooves may take a form as at 224, Fig. 2, the wire, such as shown at 226 being laid in the groove and the end pushed 10 through a cross hole through the contacts 210 to 221 where it may be soldered to insure proper electrical connection. The manually operable hour control switch may be broadly designated by the numeral 227.

Also extending forwardly through the front panel 18 is the shaft 228 of the manually operable quarter hour control switch. A hub 230 provides increased bearing length for the shaft. A hand knob 232 is secured to the outer end of 20 the shaft by the pin 234 to facilitate manual rotation of the shaft.

Within the cabinet 10, on the inner end of the shaft 228, is the arm 236, which carries a series of four contact plungers 237, 238, 239, and 240 (see Fig. 3). The plungers 237 to 240 are exactly like the plunger 208 previously described and are each provided with a compression spring 222.

The quarter hour plungers 237 to 240 although exactly like the hour plunger 208 are each given 30 a different numeral to facilitate tracing of the circuits when they are hereinafter described.

A series of forty contacts in the front panel 18 are arranged, as shown in Fig. 3, in four circular rows. The outer row has only four contacts, 35 the next to the outer row has twelve, the next to the inner row has sixteen, and the inner row has eight. The four plungers 237 to 240 are radially positioned in the arm 236 to correspond respectively with the radii of the four rows. The forty 40 contacts are numbered consecutively from 241 to 280 inclusive.

Electrically conductive wires join groups of the contacts 241 to 280 together, the groups being in turn connected by wires to the contact segments 45 104 to 107 of the main quarter hour switch 135 and the contact segments 139 to 142 of the auxiliary quarter hour switch 183. The conductive wires are shown only on the wiring diagram Fig. 9. They may be joined to the quarter hour contacts 241 to 280 by laying them in appropriate grooves (not shown) in the rear face of the front panel 18 and threading them through cross holes in the contacts in a manner as described relative to the hour contacts 210 to 221. The manually 55 operable quarter hour control switch may be broadly designated by the numeral 281.

A main manually controllable switch is provided on the front panel 18. A shaft 282 extends through the panel and through the hub 284, 60 having rotative bearing therein. A knob 286 is secured to the outer end of the shaft for manual rotation thereof.

An arm 288 contains a plunger 290 which is urged toward the panel and into electrical communication with a single contact 292 by a compression spring 222. Stop pins 294 define the "on" and "off" positions of the switch. The main manually controllable switch may be broadly designated by the numeral 291. It is normally 70 closed but may be conveniently opened to break the circuit when it is desired to discontinue operation before the selected period has expired.

The three knobs 286, 202, and 232 are provided with pointers 287, 203, and 233 respectively. The 75

two positions of the main control switch are indicated by placing the words "on" and "off" on the front of the cabinet (see Fig. 1).

Concentrically surrounding the hour control 5 knob 202 on the front of the cabinet are a series of circumferentially equally spaced numerals 1 to 12 positioned to correspond to the hour positions of the clock dial. For ornamental reasons only these numerals may be placed within circular panels as at 205. The numeral to which the pointer 203 is directed will be the hour within which the mechanism becomes operative.

Concentrically surrounding the quarter hour control knob 232 are a series of numerals arranged in four groups, each group comprising the numerals 15, 30, 45, and 60. To more clearly separate the numerals comprising a group, the raised segmental panels 235, 237, 239, and 241 may be provided.

20 If the pointer 233 is directed at any one of the four numerals in group 235, the device will become operative on the even hour. If it points to any numeral in group 237, operation will begin at quarter past the hour. If it points to any 25 numeral in group 239, operation will begin at half past, and if it points to any numeral in group 241, operation will begin at three quarters after the hour.

The group selected determines the quarter hour 30 at which the device becomes operative, while the numeral within that group indicated by the pointer 233, determines the number of minutes the device will remain operative.

On the rear panel 20 (see Fig. 8) is a manually 35 and magnetically operated switch mechanism for controlling the device. A bar 296 of electrically conductive material is fulcrumed on a screw stud 298. Hubs 300 extending laterally from the bar increase the bearing length on the stud. The 40 stud is fitted tightly and against rotation in the hub 302 which is of insulating material and extends forwardly from the face of the panel. A screw 303 is provided for making electrical contact with the bar.

45 Positioned for making electrical contact with one end of the bar 296 is the curved electrically conductive switch blade 304 which is secured to a lug of insulation 306 extending from the panel. Screws 308 may be used to secure the blade to the lug. The bar 296, at different stages in the 50 operation of the device may take the position of the broken line 295, which is the inactive position when the device is neither operating nor set to operate at a future time, or it may take the 55 position of the broken line 297, which is the position when the device is set to begin operating at some future time but that time has not yet arrived.

The position in which the bar is shown in full 60 lines is that assumed when the device has become fully operative. The switch comprising the end of the bar 296 and the blade 304 may be called the non-repeat switch and may be broadly designated by the numeral 299.

65 The other end of the bar 296 has secured thereto by rivets 310 an insulation strip 312. To the outer end of the insulation strip 312, an electrically conductive member 314 is held by the rivets 316. Member 314 has an upwardly extending tongue 318 adapted to be forced between the switch blades 320 and 322 to complete the electrical circuit between them. Broken lines 321 and 323 show the two other positions which the top end of the tongue 318 may take during the 70 different stages of the operation of the device.

The blades 320 and 322 are secured to the insulation lug 324 extending from the panel 20. Two other lugs 326 and 328 extend from the panel and are properly located to limit upward and downward movement respectively of the bar 296. The 5 switch comprising the blades 320 and 322 and the tongue 318 may be broadly designated by the numeral 329.

A push rod 330 having a push button 332 at its upper end, is vertically slidable in bearings 10 provided by bearing bosses 334 extending forwardly from the panel and bearing caps 336 secured to the bosses by screws 338. A sleeve 340 of insulating material having a head 342 is secured to the lower end of the rod 330 by the pin 15 344. A collar 346 is held to the rod by a pin 348. A spring 350 pushes the rod 330 upwardly until its movement is arrested by engagement of the top end of sleeve 340 with the bottom of a cap 336. 20

A bell-crank comprising a hub 352 with one horizontally extending arm 354 and a downwardly depending arm 356 is fulcrumed on a screw stud 358 secured in a boss 360 extending from the panel. A spring 362 has one end hooked over a pin 364 in the panel and the other end through a hole in the arm 354, thereby normally keeping the arm 354 pressed against the head 342.

The downwardly depending arm 356 is rounded 30 at the lower end. When the device is wholly inoperative and the bar 296 therefore in the position of the broken line 295, the rounded end of the arm 356 rests on a cam 366 formed on the upper edge of the bar. When the push button 35 332 is depressed to set the device for operation at some selected future time, the arm 356 is moved to the position shown by the broken line 368 where it is caught by the hook 370 formed at the end of the cam 366. The bar 296 is thus held 40 in the position of the broken line 297 until relieved by means later described. The catch mechanism for first holding, then releasing the non-repeat switch, the parts of said mechanism being numbered 332 to 370, may be broadly designated by the numeral 371 (see Fig. 8).

A solenoid coil 372 is wound of relatively fine wire on a spool comprising an insulating tube 374 with a round lower head 376 and rectangular upper head 378. Screws 380 extend through 50 holes in the upper head into tapped openings in a lug 382 extending from the panel.

A soft iron core 384 is vertically slidable in the tube 374. The lower end of core 384 is slotted to receive the connecting link 386. Pins 55 388 and 390 hinged join the link to the core 384 and the bar 296 respectively.

Energization of the solenoid 372 draws the bar 296 to the full line position shown, and if the bell-crank arm 356 is hooked up in the position 60 368 when solenoid energization takes place, it will be released and allowed to return to its normal position. Upon de-energization of the solenoid, a spring 392 draws the bar 296 downwardly until the insulation strip 312 strikes the 65 lug 328. The electro-magnetic mechanism comprising the parts numbered 372—390 may be broadly designated by the numeral 391.

A boss 394 on the rear panel is internally threaded to receive the screw socket plug 396. 70 The center terminal 398 and outer terminal 400 are connected by suitable conductors to appropriate points on the mechanism as will appear from the wiring diagram Fig. 9. The rectangular openings 402 and 404 are proportioned and 75

positioned to receive the two prong plug on the cord of a radio receiving set. A duplex cord 406 enters the back of the cabinet through a hole 408, the cord being then divided into two branches 5 410 and 412 and joined to proper terminals as seen in Fig. 9. The outer end of the cord 406 preferably is provided with a two prong plug (not shown) such as is universally used for plugging into a wall receptacle. When so connected the 10 device is preferably plugged into a suitable receptacle and the radio receiver then plugged into the device. In the wiring diagram Fig. 9, a receiver is diagrammatically shown so connected, the receiver being numbered 414. Other parts 15 of the mechanism are given the same numerals where they are schematically illustrated in Fig. 9, as they bear in Figs. 1 to 8. The operation of the device is as follows:

20 *Operation*

The operation of the device may best be described by assuming definite periods of time between which it is desired to operate a radio receiver. Let it be assumed then that a user of 25 the device at some time during the day recalls that he desires to hear a program that will begin at 3:30 p. m. and will continue for fifteen minutes. He therefore desires to set the device so that the receiver will be turned on at 3:30 30 and off at 3:45 o'clock.

To accomplish this, the knob 202 is turned until the pointer 203 points to three as shown in Fig. 1. This will place the arm 206, Fig. 3, in the horizontal position there shown. The knob 232 35 is next turned until the pointer 233 is within the segment 239. Since the program is to last only fifteen minutes, the pointer is directed to the number 15 in the segment 239. This will place the arm 236, Fig. 3, in the downwardly depending position there shown. The push button 332 40 is now depressed so that the arm 368 of the bell-crank is caught on the hook 370 leaving the bar 296 in the position 297. The device is now set to begin operation at three thirty o'clock and to 45 continue operation for fifteen minutes. It may be noted that with the bar 296 thus held in the position 297, the switch 329 is still open, that is, the blades 320 and 322 will not yet be connected by the tongue 318. Assume that the foregoing setting was made at eleven a. m.

50 At exactly three o'clock the roller 86 of the hour switch 101 (see Fig. 3) leaves the point 100 of the contact segment 59 and starts over the segment 60. No circuit of any kind is yet completed, however, until three thirty at which time the roller 124 of the main quarter hour switch 135 (see Fig. 4) leaves the point 100 of the contact segment 105 and strikes the segment 106.

A circuit is now completed (see Fig. 9) from the one side of the line 410, through arm 236, contacts 257, 258, 255, 254, 253, 252, member 106, blade 120, arm 102, arm 54, blade 82, arm 206, arm 288, solenoid coil 372, blade 304, bar 296, to the other side 412 of the line.

65 The instant the above circuit is established, the solenoid acts on the switch 329 and connects blades 320 and 322 through the tongue 318, and at the same time releases the arm 368 from the hook 370. The circuit through the solenoid 372 and the circuit through the receiver 414 (see Fig. 9) will now continue in effect until the roller 124 of the main quarter hour switch 135 passes over and off the end of the segment 106 which will occur after a period of fifteen minutes has elapsed. When it occurs, the break in the cir-

cuit by the main quarter hour switch 135 will allow the solenoid to de-energize, whereupon the bar will take the position 295 and the tongue the position 323. The device will still be set to operate at three thirty for fifteen minutes but it will not do so unless the button 332 is again depressed. If it were not for the fact that the operation included releasing the arm 356 from the hook 370 during each operating period the device would repeat, not only at three thirty the 10 next p. m. but also at three thirty a. m. which would, of course, be undesirable.

Suppose, however, that the desired program had been of half hour instead of quarter hour duration, that is, to continue from three thirty to 15 four o'clock.

The pointer 233 would then have been directed to the numeral 30 in segment 239. This would have placed the arm 236 (see Fig. 3 or 9) in electrical communication with two contacts 258 20 and 264, which would have made two contact segments 106 and 107 of the main quarter switch 135 available for continuing the circuit through the arm 120. The circuit would then have continued while the arm 120 passed over the two 25 quarter hour contact segments 106 and 107 which would have maintained the device in operation for thirty minutes, that is, from three thirty to four.

Thus far, no reason has appeared for the auxiliary quarter hour switch 183, comprising the blade 154 and contact segments 139 to 142, nor for the magnetically operated switch 329, comprising the blades 320 and 322 and the tongue 318. The described operation of the mechanism 35 for the period of three thirty to three forty-five, and the described operation for three thirty to four, was accomplished independently and without the aid of these switches. Their function may be made apparent by another example. 40

Assume that it is desired to make the device operate from three thirty to four fifteen, that is, for a period of forty-five minutes. The pointer 233 will be directed to the numeral forty-five in the segment 239. It will be recalled that when 45 the pointer is directed to any number within the segment 239, operation will begin at half after the hour, and will continue for the number of minutes represented by the numeral indicated by the pointer. 50

If then the pointer is directed to forty five in the segment 239, the arm 236 (see Fig. 3 or 9) will be in electrical communication with the three contacts 259, 265, and 272. This will connect the contact segments 106 and 107 of the main 55 quarter hour switch 135 in the circuit through the roller 124 of the switch and arm 236 of the control for two quarter hour periods. It will also connect the contact segment 142 of the auxiliary quarter hour switch 183 through the roller 60 158 of the switch, the arm 236 of the control, the switch 329, and the solenoid 372. This latter circuit through the auxiliary quarter hour switch 183 is quite independent of the circuits through the hour switch 101 and main quarter hour 65 switch 135.

With the setting for operation from three thirty to four fifteen thus selected, the push button 332 is depressed to cause the hook 370 to catch the arm 368. At three o'clock the roller 86 of the 70 hour switch 101 drops on to the segment 60. No circuit is yet completed. At three thirty the roller 124 of the main quarter hour switch 135 drops to the segment 106. Operation will now continue for half an hour while the segments 106 and 75

107 are traversed by the roller 124. At the end of this half hour of operation the roller 86 of the hour switch will drop off the end of the segment 60 and all circuits through either the 5 hour switch 101 or the main quarter hour switch 135 will be open.

While the roller 124 was thus traversing the two quarter hour segments 106 and 107, the roller 158 of the auxiliary quarter hour switch 10 was passing over the unconnected segments 140 and 141.

Therefore at the instant, or preferably a few seconds before the roller 124 drops off of the segment 107, the roller 158 will drop onto the 15 segment 142 thereby continuing the operation of the device for an additional quarter hour period. Thus two quarter hour periods were effected through the switches 101 and 135 and the third quarter hour period through the switch 183. Operation therefore was for forty-five minutes.

When the clock turns the three switches to a position where neither maintains a circuit the solenoid will be de-energized and operation will discontinue. If the manual control knobs are not 25 moved, the program may be repeated at the same hour by merely depressing the push button 332 at some time prior to three thirty of the clock.

A still more intricate series of actions takes place when the device is set, for instance, to play 30 from nine forty-five to ten forty-five. First the hour knob is turned to direct the pointer 203 to the numeral 9. This will place the arm 206, Fig. 3, over the contact 219. The quarter hour knob is then turned to direct the pointer 233 35 to the numeral 60 of the segment 241. This will place the arm 236, Fig. 3, over the four contacts 280, 276, 270, and 279. If the push button 332 is now depressed, the device is set to operate from nine forty-five to ten forty-five.

40 When nine o'clock is reached, the hour switch roller 86 drops on to the segment 66. No circuit is yet completed, and none will be completed until forty-five minutes have elapsed whereupon the main quarter hour switch roller 124 drops 45 onto the segment 107.

A circuit is then established through the segment 107 for a quarter hour period only, at the end of which period the hour switch roller 86 drops off of the segment 66 and all circuits 50 through the hour switch 101 and main quarter hour switch 135 are open. In the meantime the roller 158 of the auxiliary switch 183 has moved around to a position where it has just dropped on to the segment 142 several seconds before the 55 circuit through the switches 101 and 135 were opened. For the next three quarter hour periods, the circuit is maintained through the segments 142, 139, and 140. The operation in this case will be one quarter hour through the switches 60 101 and 135 and the other three quarters hour through the switch 183.

While the foregoing mechanism is perhaps best adapted for operating a radio receiver, it will be apparent that it may be employed to operate 65 any electrical device which a user desires to be turned on at a preselected future time and off after a selected period of time of operation has elapsed, and while the present embodiment is adapted to operate for selected quarter hour 70 periods, obviously anyone skilled in the art may adapt it to any fractional hour period within reason. Other embodiments of the invention not outside the spirit thereof will come within the scope of the appended claims.

75 We claim:

1. A device of the character described, comprising, in combination, two line conductors, a set of twelve hour conductors, hour selective means for connecting one line conductor to any one of the twelve hour conductors, a common terminal, clock operated means for consecutively connecting the twelve hour conductors to the common terminal in twelve hours, a set of four quarter hour conductors, a second clock operated means for connecting the common terminal 5 to the four quarter hour conductors consecutively in one hour, and quarter hour selective means adapted to be moved to different positions to connect either one, two, three, or four of the quarter hour conductors to the other line conductor, whereby a circuit is completed between the line conductors whenever the first clock operated means has one of the hour conductors connected to the common terminal and the second clock operated means has one of the quarter 10 hour conductors connected to the common terminal.

2. The structure defined in claim 1 with a nonrepeat switch series connected in the circuit, resilient means urging the switch to open position, manual means for moving said switch to a closed position, a catch to hold the switch to closed position, and electromagnetic means including a coil series connected in the circuit and operative to release said catch and itself hold 25 the switch closed until said clock operated means opens the circuit, then release said switch to be moved to open position by said resilient means.

3. A device of the character described, comprising, in combination, first and second line conductors, a set of twelve hour conductors, hour selective means for connecting the first line conductor to any one of the twelve hour conductors, a common terminal, clock operated means for consecutively connecting the twelve hour 30 conductors to the common terminal in a period of twelve hours, a set comprising a first, a second, a third, and a fourth quarter hour conductor, a second clock operated means for connecting the common terminal of the first, second, 35 third, and fourth quarter hour conductors consecutively within each hour, a second set comprising a first, a second, a third, and a fourth quarter hour conductor, a second common terminal connected to the first line conductor, a third clock operated means for connecting the second common terminal consecutively to the first, second, and third quarter hour conductors of the second quarter hour set in a period of 40 three quarters of an hour, and quarter hour selective means to connect the second line conductor to one quarter hour conductor or to groups of two, three or four quarter hour 45 conductors.

4. The structure defined in claim 3 wherein 50 the quarter hour selective means is such that part of the quarter hour conductors in a group selected may be in the first set and the remainder in the second set, whereby any group starting with such a conductor of the first quarter hour set as leaves insufficient quarter hour 55 conductors for the desired group, from the starting point to the next even hour period, will be completed with conductors of the second set.

5. The structure defined in claim 3 with switch 60 mechanism comprising a series switch in the first line conductor, resilient means urging said switch to open position, manual means for moving said switch to closed position, a catch to hold the switch to the closed position, an electromag- 65

net including a series coil in the first line conductor operative to energize said electromagnet and release said catch and thereafter hold said switch closed magnetically until said clock operated means opens the circuit, then release said switch to be moved to open position by said resilient means, and a second series switch in that part of the first line conductor which extends to the second common conductor, adapted to be held closed by said electromagnetic means only as long as it remains energized.

6. The combination, in a device of the character described, of a twelve contact clock operated hour switch, a main four contact clock operated quarter hour switch, a conductor connecting the common points of the said hour switch and main quarter hour switches, an auxiliary four contact clock operated quarter hour switch, first and second line conductors of opposite polarity, the first being connected to the common point of the auxiliary quarter hour switch, hour selective means to connect the first line conductor to one of the twelve contacts on the hour switch, quarter hour selective means to connect the second line conductor to one or to a selected group not exceeding four consecutive contacts which may comprise all contacts of the main quarter hour switch or part from the main and part from the auxiliary quarter hour switch.

7. The combination in a timing device of a clock operated hour switch having a first common terminal connectable to twelve terminals consecutively within twelve hours, a clock operated main fractional hour switch having the same first common terminal connectable to a series of fractional hour terminals consecutively within one hour, an auxiliary clock operated fractional hour switch having a second common terminal connectable to a series of fractional hour terminals consecutively within one hour, an hour selective device comprising a third common terminal selectively connectable to twelve terminals said twelve terminals being in electrical communication respectively with the twelve terminals of the hour switch, a first line conductor com-

prising a main part and two branches in parallel, the first branch being connected to the third common terminal and the second branch to the second common terminal, and a fractional hour selective device comprising a fourth common terminal connectable selectively to groups of fractional hour terminals of the main fractional hour switch and the auxiliary fractional hour switch, and a second line conductor in electrical communication with the fourth common terminal.

8. The structure defined in claim 7, with control switch mechanism comprising a series control switch in the main part of the first line conductor, a second series control switch in the second branch of the first line conductor, resilient means urging both control switches to an open position, an electromagnet adapted when energized to hold both control switches in the closed position, a coil on said electromagnet series connected in the main part of the first line conductor, manual means to move the first control switch to closed position, and a catch for holding the first control switch in the closed position when manually closed, said electromagnetic means being operative when energized to first release said catch, then magnetically hold both control switches closed until deenergized.

9. The structure defined in claim 7 wherein the clock operated switches and the hour and fractional hour selective devices comprise circular rows of terminals connectable by rotatable conductive elements in electrical communication with, and swingable around the said common terminals.

10. The structure defined in claim 7 wherein the clock operated switches comprise circular rows of terminals connectable by rotatable conductive elements in electrical communication with, and swingable around, the said common terminals, and the terminals of the circular rows are each individually adjustable to advance or retard the break with the rotating element.
